UNITED STATES PATENT OFFICE

ELBERT E. THOMAS, OF PAMPA, TEXAS

HAT DISPLAY CASE

Application filed June 28, 1930. Serial No. 464,820.

The present invention consists of a hat display case, especially adapted for use in displaying men's hats in stores, and has for an object to arrange different style hats of uniform size on one tray, or rack of the case, to permit a selection to be made by a customer in an expeditious manner, without the necessity of detaining the customer until different styles of hats, stored in a plurality of boxes, cases, etc., are exhibited to him, for the purpose of making a selection suitable to his whim or fancy.

Frequently sales of hats are lost by merchants because of the indolence or inadvertence of employees in not showing various styles of hats stored away in cases or boxes, and it is therefore a further object of the present invention to provide hat supporting or displaying means which is constantly in display position and may be mounted on top of a suit display case, or the like, so as to occupy a minimum amount of space, yet being so constructed as to permit convenient accessibility thereto at all times.

A still further object of the invention is to provide means for retaining the various styles of hats in display position at all times, free from contact with dust or dirt, the hats being arranged to permit individual removal therefrom from the racks or trays without in any way disturbing adjacent hats.

Other objects of the present invention will be apparent from the following description of the present preferred form of the device, taken in connection with the accompanying drawings, wherein

Fig. 1 is a fragmentary top plan view of a hat case, constructed in accordance with the present invention, showing to advantage the hat supporting trays;

Fig. 2 is a front elevational view of the same;

Fig. 3 is a vertical sectional view of a hat display case, constructed in accordance with the present invention, illustrating the application thereof, dotted lines being used to show the position of one of the hat trays preparatory to removing the same from the case;

Fig. 4 is a side elevational view of one of

the hat trays and element employed for removing same from the hat display case;

Fig. 5 is a perspective view of a unit supporting base, constructed in accordance with the present invention;

Fig. 6 is a fragmentary perspective view of one of the hat trays; and,

Fig. 7 is a perspective view of the handle used for removing a hat tray from its case and replacing it in the latter.

In order to illustrate the application of the present invention, I have shown a portion of a supporting structure 8, which, in the present instance, represents a suit display case, as customarily used in stores, especially in men's stores. The hat display case constructed in accordance with the present invention may be of any desired size and configuration, but in the present drawings I have shown an oblong type of case 9, provided with sliding doors 10, having transparent panels therein, as is well known in the art. The bottom of the hat display case 9 is formed to provide a movable platform 11, which may be of such a size as to accommodate any number of hat supporting trays, hereinafter described. In the present instance the platform is shown as adapted for the reception of two (2) trays and consequently, a pair of tray receiving recesses 12 are provided in the top of the platform. The bottom of the platform is provided with a series of runners 13, upon which the platform slides when pressure is exerted thereon to urge the same outwardly through the front of the case when the doors 10 are open. For the purpose of actuating the platform 11, I provide a bearing block 14, the upper end of which is bifurcated and has a bell crank lever 15 pivotally mounted between the ramifications of the block. One end of the bell crank lever is pivotally engaged with one end of an operating bar 16, the opposite end of the latter being pivotally engaged with a bracket 17, carried by the rear wall of the hat display case 9. The outer end of the bell crank lever is provided with an opening 18 and is adapted to receive a stud 19, formed on a handle 20. When the stud 19 is inserted

in the opening 18 and pressure exerted down-

wardly on the handle 20, the platform 11 will be caused to move outwardly in the case in a manifest manner.

A pair of trays are adapted to be mounted on the platform 11, each of which embodies a supporting plate 21, which has a supporting standard 22 extending upwardly from the center thereof, the standard being equipped with two (2) series of hat supporting elements or frames 23. The elements or frames of each series are arranged in superposed relation, but the elements of the different series are off-set so as to lie in different horizontal planes, as shown to advantage in Figs. 3, 4 and 6. Consequently, space is economized in that the hat brims of one series may overlap the hat brims of the other series, without interference, yet permitting any one hat to be removed without disturbing an adjacent hat. Preferably the supporting standard 22 is composed of a wire strand, bent into U-shape with the frames 23 formed integral therewith and also made of wire. Each frame is preferably composed of a single strand of wire, the terminals of which are fixedly secured to the standard 22, while the intermediate portion thereof is reversely folded to provide a substantially semi-ovoid hat crown embracing portion 24. The sides of the frame beyond the hat crown embracing portion 24 are vertically off-set, as indicated at 25, to permit the hat crown embracing portion to be flexed outwardly, without impinging against the sides of the frame. Instead of fixedly engaging the terminals of the wire strand with the standard 22, these terminals may be convoluted around the standard, as indicated at 23', so as to permit adjustment of the frames at the option of the user.

The base plates 21 may be of any desired configuration and are adapted to be slidably received in the recesses 12 of the platform 11. Each of the plates is provided with an extension 26, which is thickened and provided with an opening 27, adapted for the reception of a finger 28 formed on one end of the handle 20. Consequently, after the platform has been urged outwardly in the manner already described, any one of the hat trays may be removed from the platform by engaging the finger of the handle 20 in the opening 27 of the tray desired and the tray removed from the hat display case, for the purpose of exhibiting the hats carried by the tray to a prospective customer. It is to be understood that each tray is adapted to carry hats of a uniform size, but of different styles, so that the prospective customer may select the style which he desires in his own size with convenience and expedition. After the selection has been made, the tray may be replaced by the handle 20, in an obvious manner, after which the handle is re-engaged with the bell crank lever 15 and pressure exerted upward-

ly thereon, so as to urge the tray supporting platform 11 rearwardly in the hat display case.

While the device of the present invention is especially adapted for use in smaller towns, where a comparatively small number of hats is carried by each store, it is nevertheless believed to be apparent that the present invention may be used to advantage in any store, especially where it is desired to economize on space. The hat display case of this invention may be mounted as above stated on the tops of suit display cases, or may be mounted on shelves or other supporting objects, above the reach of the average person, yet by reason of the present structure, the hats are in convenient accessibility at all times. By arranging the different style hats of one size on a single tray, a great deal of time is saved, not only on the part of the prospective customer, but likewise on the part of the sales-person.

It is to be understood that while I have herein shown and described a preferred embodiment of this invention, I am nevertheless aware that various changes may be made therein, especially in the means for operating the tray supporting platforms, within the scope of the claims hereto appended.

What is claimed is:

1. In a hat display case, a supporting platform equipped with hat trays, each of said trays embodying two series of hat supporting frames arranged in different horizontal planes, means carried by the platform and engageable with the case to urge the platform outwardly from the latter, said means embodying additional means for removing any one of the hat trays from the platform when the latter is in an outward position.

2. In a hat display case, in combination with a supporting structure, a base mounted on said supporting structure, a plurality of trays slidably and detachably mounted on said base, hat supporting means carried by each of said trays, and operating mechanism operable with said base and with said supporting structure for urging said base over said supporting structure.

3. For use in displaying hats, a supporting structure, a case mounted on the supporting structure, a slidable hat tray carrying platform mounted on the supporting structure within said case, means operatively connected to the case and platform for urging the latter outwardly, said means embodying additional means for individually removing any one of the hat trays.

ELBERT F. THOMAS.
